UNITED STATES PATENT OFFICE

ISAAC A. BAUM, OF CHICAGO, ILLINOIS

REINFORCED METAL JAMB

Application filed April 7, 1930. Serial No. 442,243.

My invention relates to building construction and more particularly to metal jamb construction.

An object of my invention is to provide a metal jamb of channel shape in which the side plane of the flanges shall be coincident with the plane of the plaster and still provide a firm and unyielding engagement with the masonry wall. It is common to provide jamb structures of the full width of the plaster or a great width, in order to insure proper decorative effect, but such structures should include the important feature of rigid mounting relative to the wall. Thus plaster cracks occur adjacent to the junction between the jamb structure and the plaster.

I have accomplished the desired result in a very simple manner and at the same time provide for the connection of an effective wall anchor.

The invention will be more readily understood by reference to the accompanying drawing, in which

Fig. 1 is a sectional view in perspective of a device constructed in accordance with my invention;

Fig. 2 is a horizontal sectional view thereof;

Fig. 3 is a sectional view in perspective of a modified form of the device shown in Fig. 1; and

Fig. 4 is a horizontal sectional view thereof.

By reference to the drawing, it will be seen that my invention comprises a channel shaped metal frame, generally indicated at 10 having the web 11, and door stop 12, and channel flanges 13. The metal frame 40 is adapted to overlie and be separated from a tile wall 14. Connected to the web and flanges is the bracing member 15, having the spacing portion 16. The bracing member is adapted to have direct contact with the faces of the tile 14. If desired, the anchors 17 may be provided having the hooks 18 adapted to be inserted in suitable apertures 19 provided in the bracing members 15. The anchor is inserted between two tile 50 and is embedded in mortar, thus providing

a firm, permanent anchor against horizontal stresses.

In the form shown in Figs. 1 and 2, the angular portion 20 contacting the inner face of the web 15 is disposed toward the inside 55 of the frame.

The modified form shown in Figs. 3 and 4 is identical with that shown in Figs. 1 and 2, except that the angular portion 20 is disposed in the opposite direction, or 60 toward the flanges of the frame member. In the latter instance, as is shown, the web of the member has direct contact with the end face of the tile wall.

The installation of the frame member 65 herein disclosed is simple and may be done readily by unskilled labor. The complete device may be fabricated at the shop before shipping to the job, thus saving considerable time and expense in the fitting 70 of the same to the wall.

Obviously, the spacing portion 16 serves also as a plaster defining portion, the plaster being applied flush with the channel flanges 13. 75

Thus, it will be seen that I have provided a simple, yet rigid frame member which is braced against lateral and angular stresses due to the force exerted against the door stop 12 when in use. 80

While it is possible that one skilled in the construction herein illustrated may devise variations and modifications in the construction shown, and I do not wish to be limited except as indicated in the appended 85 claims.

I claim:

1. In metal frame construction, the combination of a channel shaped jamb member, the flanges of which are spaced from the 90 sides of a masonry wall, and metal strips having their flanges bent to contact the inside faces of the flanges and web to provide a box section at the corners of the jamb and their web portions in rigid engagement with 95 an unplastered portion of the masonry wall, and wall anchors engaging said strips.

2. A metal frame structure comprising a channel-shaped jamb member the flanges of which are adapted to embrace the sides of 100

an unplastered portion of a masonry wall in spaced relation thereto, the side plane of the flanges adapted to lie coincident with the plane of a plastered portion of the wall and 5 flanged filler members rigidly secured to said jamb member and adapted to directly engage said unplastered portion of the wall.

3. A metal frame structure comprising a channel-shaped jamb member the flanges of 10 which are adapted to embrace the sides of a masonry wall in spaced relation thereto, a flanged filler having one flange connected to a flange of the jamb member and another flange connected to the web of the jamb 15 member and a web intermediate said flanges adapted to directly engage an unplastered portion of said wall.

4. A metal frame structure comprising a channel-shaped jamb member the flanges of 20 which are adapted to embrace the sides of a masonry wall in spaced relation thereto, a channel shaped filler having its flanges contacting with one of the flanges of said jamb member and the outer face of its web 25 adapted to rigidly engage an unplastered portion of said wall whereby upon assembling said structure with said wall said structure rigidly engages said wall.

5. In combination with a masonry wall, a 20 metallic frame structure, said structure comprising a metal channel-shaped jamb having substantially straight flanges adapted to embrace said wall, the side plane of the flanges adapted to lie coincident with the 25 plane of a plaster portion of the wall, a flanged filler member rigidly secured to said jamb member and disposed in close engagement with an unplastered portion of said wall.

49 In testimony whereof I have affixed my signature.

ISAAC A. BAUM.
